UNITED STATES PATENT OFFICE.

EDWIN DUVALL, OF SHARONVILLE, OHIO, ASSIGNOR TO THE DUVALL COAL DOCK COMPANY, OF LEWISBURG, OHIO.

CAR-UNLOADING APPARATUS.

1,226,483.

Specification of Letters Patent. Patented May 15, 1917.

Application filed February 23, 1916. Serial No. 80,023.

To all whom it may concern:

Be it known that I, EDWIN DUVALL, a citizen of the United States of America, residing at Sharonville, in the county of Hamilton and State of Ohio, have invented certain new and useful Improvements in Car-Unloading Apparatus, of which the following is a specification, reference being had therein to the accompanying drawing.

This invention relates to a car unloading apparatus and has for its object the production of a simple and efficient means whereby a car may be run into a drum and the drum inverted for the purpose of unloading material carried by a car or other vehicle.

Another object of this invention is the production of a simple and efficient means for rotating the drum after the car has once been positioned therein.

With these and other objects in view, this invention consists of certain novel combinations, constructions, and arrangements of parts, as will be hereinafter fully described and claimed.

In the accompanying drawings:—

Figure 1 is a top plan view of the apparatus.

Fig. 2 is a side elevation of the drum used in connection with the present invention.

Fig. 3 is a central vertical section through the drum.

Fig. 4 is a section taken on line 4—4 of Fig. 3.

Fig. 5 is a central transverse section 35 through the drum, showing the same in an inverted position.

Fig. 6 is a diagrammatic view, showing the manner of rotating the drum upon the supporting tracks.

Fig. 7 is a vertical section through one of the car engaging beams carried by the inner frame of the drum.

Fig. 8 is a section taken on line 8—8 of Fig. 7.

Fig. 9 is an enlarged longitudinal section through the base platform of the inner frame of the drum.

Fig. 10 is an enlarged section showing the manner of attaching the anchoring or operating cable which is adapted to cause the drum to travel upon the supporting tracks.

Referring to the accompanying drawings by numerals it will be seen that 1 designates the main or supporting trestle-work which

comprises a plurality of transversely extending ties 2 upon which ties 2 are mounted the side rails 3 and the central rail 4. By carefully considering Fig. 1, it will be seen that the side rails 3 are arranged in pairs and are adapted to receive the circumferentially extending channel irons 5 carried by the drum 6. This drum 6 extends entirely across the trestle-work 1 and has one end thereof working upon the opposite pairs of supporting rails 3 as clearly illustrated in Fig. 1 of the drawings. Upon a careful consideration of Fig. 1 of the drawings, it will be seen that the channel plates 5 are arranged in close proximity to each other adjacent the terminal ends of the drum 6. A secondary arranged channel plate 7 is carried intermediate the ends of the drum 6 as illustrated in Fig. 1 and this plate 7 is adapted to travel upon the centrally located rail 4.

By carefully considering Figs. 3 and 5 of the drawings, it will be seen that these channel irons 5 and 7 extend around the outer circumference of the drum 6 and constitute reinforcing bands therefor as well as runners for traveling upon the respective rails 3 and 4.

An inner frame-work 8 is mounted within the drum 6 and comprises a plurality of beams which are so arranged as to constitute a square housing in cross section as illustrated in Fig. 3. A plurality of car bracing beams 9 are carried by the inner frame 8 and a covering or lining plate 10 is fitted upon the inner face of the car bracing beams 9. The inner drum 8 is also provided with a lining 11 of suitable construction, such for instance as sheet metal, or any other convenient material which may be found advisable. The frame 8 is provided with a chute portion 12, which chute portion 12 communicates with a plurality of elongated slots 13 formed in the upper portion of the drum 6.

The base portion 14 of the frame 8 is provided with a plurality of spaced rails 15 for the purpose of permitting the car 16 to travel into the drum 6 and upon the rails 15 from the trackways 17 communicating with the rails 15.

A plurality of eyes 18 are secured to the bottom platform 14 and a plurality of chains 19 are secured to the eyes 18 and are pro-

vided' with hooks 20 for the purpose of fitting over the upper or outer edges of the car 16, as clearly illustrated in Fig. 3 of the drawings.

5 A bracing plate 21 is carried by the lining 10 and is provided with a substantially V-shaped channel groove 22 upon the outer edge thereof for the purpose of receiving the lower corner of the car frame or body 10 16, as clearly illustrated in Fig. 3 of the drawings. An abutment block 23 is slidably mounted upon the bracing beam 9 and is adapted to engage the side of the car 16 and constitute a brace or support therefor, while 15 the drum 6 is being rotated, in one direction. A plurality of supporting bolts 24 are carried by the beam 23 and these bolts 24 pass through the elongated slots 25 formed in the beams 9, as illustrated clearly 20 in Figs. 7 and 8 of the drawings. It of course should be understood that the beam 23 as well as the plate 21 is provided with notched portions 26 for the purpose of permitting the chains 19 to pass therethrough 25 and remain in a taut position.

By carefully considering Fig. 1 of the drawings, it will be seen that the channel plates 5 upon the respective ends of the drum 6 are placed at a sufficient distance 30 apart to permit the operating cables 27 to pass therebetween for the purpose of operating the rotating drum 6. The cables 27 are anchored by means of an anchor member 28 as illustrated in Fig. 10 in any desired position 35 as for instance upon one side of the discharge pit 29. It should be understood that the discharge pit 29 is placed below the track or trestle-work 1 and so arranged as to have the rails 3 and 4 extend over the pit 40 29, thereby permitting the material carried by the car 16 to be emptied into a car 16', adapted to be placed within the pit 29.

A suitable windlass 30 is mounted in any desired position adjacent the track or trestle-work 1 and the cable 27 is wound upon the windlass 30 as illustrated in diagram in Fig. 6, the cable first passing around the drum 6 for one complete revolution between the channel plates 5 carried upon the ends

of the drum 6 as illustrated clearly in Fig. 50 1 of the drawings.

The rails 3 and 4 are arranged so as to incline away from the windlass 30 and it should be understood that any suitable mechanism may be employed for operating the 55 windlass 30 and winding the cable 27 upon the windlass 30.

The operation of the device above described is as follows:

The drum 6 is in the position as shown 60 in Fig. 1 and a car loaded with coal, broken stone, or other material, is run into the hollow drum 6 upon the rails 15 and is then anchored in a set position by means of the chains 19. After the car has been placed in a 65 set position, the windlass 30 is operated so as to wind the cable 27 thereon and cause the drum 6 to move in the direction of the arrow indicated in Fig. 6 of the drawings. After the drum 6 has made one half a revolution and been drawn to the position shown in Fig. 5, the material within the car 16 will be discharged out through the discharge chute 12 and cause the material from the 70 car 16 to be deposited into the car 16' positioned within the pit 29, upon the rails 31. 75

After the windlass 30 has been released, however, the drum 6 will return to its normal position through the force of gravity in view of the fact that the rails 3 and 4 are 80 inclined downwardly away from the windlass 30.

What I claim is:

In a car dumping machine, the combination 85 with a main cylinder, a frame positioned within said main cylinder, a plurality of bracing bars secured to said main cylinder, an adjustable bracing beam secured to said bracing bars, a stationary socket plate secured to said bracing bars, and said socket 90 plate adapted to engage the lower edge of a car body for bracing the same while dumping and assisting in holding said car body against displacement.

In testimony whereof I hereunto affix my 95 signature.

EDWIN DUVALL.
